FLASHLIGHT AND BATTERY DISPLAY PACK

Arthur H. Moore, Fairfield, Conn., assignor to The Bridgeport Metal Goods Mfg. Co., Bridgeport, Conn., a corporation of Connecticut

Application February 21, 1957, Serial No. 44,951

Term of patent 14 years

(Cl. D80—5)

FIG. 1

FIG. 3

Fig. 1 is a perspective view of a flashlight and battery display pack showing my new design;

Fig. 2 is a side elevation of the display pack shown in Fig. 1; and

Fig. 3 is a front elevation of the display pack shown in Figs. 1 and 2.

The dominant features of my design reside in those portions shown by means of full lines in the drawing.

I claim:

The ornamental design for a flashlight and battery display pack, as shown and described.
